(57) **CLAIM**

The ornamental design for a catheter strain relief clip, as shown and described.

DESCRIPTION

FIG. 1 is a perspective view of a catheter strain relief clip embodying my new design;

FIG. 2 is a top view of the catheter strain relief clip shown in FIG. 1;

FIG. 3 is a bottom view top of the catheter strain relief clip shown in FIG. 1;

FIG. 4 is a side view of a first side of the catheter strain relief clip shown in FIG. 1;

FIG. 5 is a side view of a second side of the catheter strain relief clip shown in FIG. 1;

FIG. 6 is an end view of a first end of the catheter strain relief clip shown in FIG. 1; and,

FIG. 7 is an end view of a second end of the catheter strain relief clip shown in FIG. 1.

The broken lines in the drawings represent unclaimed environmental subject matter illustrating the design in use and form no part of the claim.
